UNITED STATES PATENT OFFICE.

JOHN COULSON, OF WILKINSBURG, AND CLARENCE J. ROTTMANN, OF PITTSBURGH, PENNSYLVANIA, ASSIGNORS TO WESTINGHOUSE ELECTRIC & MANUFACTURING COMPANY, A CORPORATION OF PENNSYLVANIA.

TERMINAL PROTECTOR FOR ELECTROLYTIC CONDENSERS AND RECTIFIERS.

Application filed March 13, 1918, Serial No. 222,187. Renewed May 15, 1922. Serial No. 561,167.

To all whom it may concern:

Be it known that we, JOHN COULSON, a subject of the King of Great Britain, and a resident of Wilkinsburg, in the county of Allegheny and State of Pennsylvania, and CLARENCE J. ROTTMANN, a citizen of the United States, and a resident of Pittsburgh, in the county of Allegheny and State of Pennsylvania, have invented a new and useful Improvement in Terminal Protectors for Electrolytic Condensers and Rectifiers, of which the following is a specification.

Our invention relates to an improved form of terminal for electrolytic condensers, lightning arresters, rectifiers and the like, in which the electric current enters and leaves an electrolytic bath by means of metallic terminals.

It is commonly known that the terminals in such pieces of apparatus become corroded, during use, at the point where they protrude from the electrolyte into the air or other gases above the electrolyte. The rate of this corrosion varies somewhat with various electrolytes, their chemical composition and their concentration. In time, the corrosion reaches such a depth as to so weaken the metal of the electrode terminal that the electrode breaks off from its own weight or from jars or vibrations to which it may be subjected. Some electrolytes, which are satisfactory from their electrical behavior, are not applicable to commercial use on account of this rapid deterioration of their terminals. Other electrolytes, which are satisfactory as first supplied, in a short time become so concentrated by evaporation that they attack and corrode the terminals.

Furthermore, this corrosion or incrustation of the terminals, particularly in electrolytic condensers, is a source of a serious current leakage and, consequently, of a material watt loss.

We have discovered that this corrosion of the terminals at the juncture of the electrolyte and supernatent gas, and all salt formation upon the terminals at this point, together with the usual current leakage caused by this corrosion, are eliminated if the terminals are maintained in an atmosphere saturated with water vapor. The primary object of our present invention, resides, therefore, in the provision of a simple and effective means for maintaining an

atmosphere of water vapor about the electrode terminals immediately above the surface of the electrolyte.

In the accompanying drawings, in the views of which similar parts are indicated by the same reference characters, Fig. 1 is a perspective view of a condenser illustrating an embodiment of our invention. Fig. 2 is a fragmentary sectional view taken longitudinally through a protector sleeve such as we provide for the electrode terminals, showing the manner of mounting it upon the terminal.

In order to insure a clear understanding of our invention, we have disclosed it in connection with an electrolytic condenser, including a jar or container 10, which may be of glass and the plate electrodes 11 of metal, as for instance, aluminum. The electrodes have the usual terminals 12 which may be formed integrally with the plates and be so disposed as to project above the surface of the liquid electrolyte 13.

Our invention consists in mounting a sleeve 14 about each of the terminals 12, the lower end of the sleeve being open and disposed at an appreciable distance below the surface of the electrolyte and the upper end being closed, as indicated at 15, by wax or other suitable material which also forms a means for securing the sleeve to the terminal.

These sleeves may be formed of any suitable nonconducting material which will not be affected by moisture or by the electrolyte and which will not affect the electrolyte. Glass is very satisfactory for this purpose. The sealing material 15 may be any suitable sealing wax, gum or rubber, all of these materials having been used with success.

The space within the tube or sleeve, above the surface of the electrolyte, becomes saturated with water vapor and may contain some of the gases given off during the operation of the condenser. Because of the presence of the saturated atmosphere in the tubes 14, no corrosion of the electrode terminals will occur where they pass from the electrolyte and no deposits of crystallized salts will be formed thereon. The life of the condenser is thereby materially increased and one source of current leakage is eliminated.

We have found, from actual practice, that these protector sleeves constitute a satisfac-

tory and practical means of protecting the electrode terminals, extended tests of electrolytic condensers, over periods of several months, having been made with no signs of 5 corrosion of the terminals.

It will, of course, be appreciated that we do not wish to restrict our invention to the terminals of electrolytic condensers, as it is applicable to all apparatus having terminals, 10 or parts of electrodes, which pass from an air or a gas medium into a liquid electrolyte. We therefore reserve the right to apply our invention to all processes to which it may be adapted and to make any changes 15 which we may desire and which may be within the scope of the claims.

We claim as our invention:

1. In electrical apparatus, a terminal projecting above the surface of an electrolyte 20 and means for maintaining a water-saturated atmosphere about the terminal immediately above such surface, said means including a sleeve closed at one end.
2. In electrical apparatus a terminal projecting above the surface of an electrolyte and a sleeve disposed with an open end below the surface of the electrolyte and having its other end, through which the terminal passes, closed.
3. In electrical apparatus a terminal projecting above the surface of an electrolyte, 30 and a sleeve surrounding a portion of the terminal and spaced therefrom, one end of the

sleeve being sealed about the terminal and 35 the opposite end being disposed below the surface of the electrolyte.

4. In electrical apparatus an electrode having a terminal, a sleeve surrounding a portion of the terminal and spaced therefrom, and connecting means between one end of the sleeve and the terminal whereby 40 such end of the sleeve is closed and the sleeve is secured to the terminal.

5. The combination with an electrolytic 45 condenser including an electrolyte, electrodes disposed therein and terminals for the electrodes projecting through the surface of the electrolyte, of sleeves having closed ends through which the terminals project and 50 open ends extending below the surface of the electrolyte.

6. The combination with an electrolytic condenser including an electrolyte, electrodes disposed within the electrolyte, and terminals for the electrodes projecting from the electrolyte, of means carried by the terminals providing chambers about the portions 55 of the terminals immediately above the surface of the electrolyte, with the lower portions of the chambers projecting and opening 60 into the electrolyte.

In testimony whereof, we have hereunto subscribed our names this 28th day of Feb., 1918.

JOHN COULSON.
CLARENCE J. ROTTMANN.
